(57) **CLAIM**

The ornamental design for a tweezers with hair trimmer, as shown and described.

DESCRIPTION

FIG. 1 is a top perspective view of the tweezers with hair trimmer showing my new design;

FIG. 2 is a right side view of the tweezers with hair trimmer;

FIG. 3 is a top view of the tweezers with hair trimmer thereof;

FIG. 4 is a left side view of the tweezers with hair trimmer

thereof;

FIG. 5 is a bottom view of the tweezers with hair trimmer

thereof;

FIG. 6 is a front end view of the tweezers with hair trimmer

thereof;

FIG. 7 is a rear end view of the tweezers with hair trimmer

thereof; and,

FIG. 8 is a top perspective view of the tweezers with hair trimmer showing the hair trimmer in semi-rotated position.

The broken lines immediately adjacent the shaded areas represent the bounds of the claim and all other broken lines are for illustrative purposes only. None of the broken lines form a

part of the claimed design.
